UNITED STATES PATENT OFFICE

2,004,790

ELECTRON DISCHARGE DEVICE

Friedrich W. Hehlgans, Berlin-Hermsdorf, Germany, assignor to General Electric Company, a corporation of New York

Application May 11, 1933, Serial No. 670,556
In Germany May 27, 1932

5 Claims. (Cl. 179—100.3)

The invention relates to electron discharge devices, such as cathode-ray tubes, employed for the purposes of sound recording, television, etc. An object of the present invention is to provide 5 a circuit arrangement and apparatus for increasing by regenerative action, the electrical impulses applied to the cathode-ray tube whereby the light output and control of the tube are enhanced.

The invention is based on the following principle: If alternating current voltages are applied to the control electrode or Wehnelt cylinder of a cathode-ray tube, as used for sound recording, and a telephone receiver is connected in the anode circuit of the tube, electric impulses of considerable strength are found to exist in the anode circuit. These impulses represent a faithful reproduction, in amplified form, of the voltages applied to the control cylinder.

In accordance with the present invention, this principle is employed for increasing the light output of the cathode-ray tube in such a manner that the oscillations occurring in the anode circuit of the tube are applied to the control circuit of the tube in such phase as to add to the original 20 alternating current voltage. The invention will be better understood when reference is made to the following description and the accompanying drawing in which Fig. 1 shows diagrammatically a system embodying the invention and Fig. 2 25 illustrates an alternative arrangement.

In Fig. 1, numeral 1 designates a microphone transmitter connected in series with an energizing battery 2 and the primary of a transformer 3. The secondary of the transformer is connected 30 to the input circuit of a thermionic amplifier 4 of ordinary construction. This amplifier includes an electrostatic control member 5, a filamentary cathode 6 and an anode 7. The filament and the anode are connected to different potential taps on a common battery 8 or other source of potential. The control member 5 is connected to the negative end of the battery in such a manner as to obtain a constant negative bias.

The output circuit of the amplifier 4 is connected to the control circuit of a cathode-ray tube 9 by means of a well-known capacity and resistance coupling consisting of a capacitor 10 and resistances 11 and 12. If desired, an inductive or transformer coupling may be used.

50 The cathode-ray tube is of ordinary type and includes a cathode 13, a control electrode or Wehnelt cylinder 14 and an anode 15 in the form of a circular plate of metal provided with a central aperture 16 for the cathode rays. At the end of 55 the envelope, opposite from the cathode, there

is a screen 17 of well-known form which fluoresces when struck by electrons and the light therefrom is radiated onto a moving film 18. The cathode 13, control member 14 and the anode 15 of the cathode-ray tube are connected to various potential taps on the common battery 8. As in the case of the amplifier 4, the control member of the cathode-ray tube is also preferably maintained at a constant negative potential.

5 The cathode-ray tube may be highly evacuated but preferably contains an inert gas at a relatively low pressure in which case the anode is charged to a suitable potential, for example of approximately 500 to 800 volts, by the battery 8 or other source of potential, through a protective 10 resistance 19.

The purpose of the cathode-ray tube is to translate the electrical undulations applied to the cylinder 14 into light images which are photographically reproduced on the sound record 18.

20 In accordance with my invention, a regenerative circuit is provided between the anode and control electrode circuits of the cathode-ray tube in order to increase the control exercised by the cylinder 14 on the electron beam striking the fluorescent screen 17. Thus increased control of the intensity of the light spot and of the photographic image on the sound track 18 is obtained.

25 As shown in Fig. 1, this regenerative effect is produced by means of a back-coupling through a conductor 20 connected to a point in the anode circuit between the anode 15 and the resistance 19. This conductor has in series therewith a capacitor 21, fixed or adjustable, also a resistance 22 which is connected to a point between the 30 secondary winding of the transformer 3 and an adjustable resistance 23 inserted in the control circuit of the amplifier 4. The relative magnitude of the resistances 22 and 23 determines the 35 voltage increment which is applied to the input 40 of the amplifier 4 and hence, provides an adjustment of the increased voltage impressed on the control member of the cathode-ray tube. It is apparent that by reason of the introduction of the amplifier between the source of voltage variations and the control member of the cathode-ray tube the energy fed back in this manner is in the proper voltage phase relation with respect to the voltages applied to the amplifier 4 so that 45 an amplification of these voltages and therefore 50 an increase of the output of the cathode-ray tube in terms of augmented light intensity of the spot on the fluorescent screen are obtained.

55 It is possible to obtain regenerative current of the proper phase relation without the use of the 55

additional amplifier 4. In this case, an additional electrode may be arranged between the cathode and the Wehnelt cylinder of the cathode-ray tube and the regenerative voltage taken from the circuit which includes this auxiliary electrode. The electrode may be formed for example as a grid or plate with a central opening and is positively charged. Fig. 2 shows such a system.

As illustrated in Fig. 2, the microphone transmitter 1 is connected in the local circuit and produces voltage variations between the control element or Wehnelt cylinder 14 and the cathode 13 of the cathode-ray tube 9. As in the case of Fig. 1, there is also provided an anode 15 with a central aperture 16 through which the electrons pass on their way to the fluorescent screen 17.

Between the cathode and the control cylinder, there is an electrode 24 having a central aperture 25 in line with the opening in the cylinder 4 and the aperture 16 in the anode 15. The electrode 24 is connected through the current-limiting resistance 26 to an intermediate positive terminal on the common battery or source of energy supply 8. A regenerative coupling is connected between the electrode 24 and the input circuit of the cathode-ray tube through a capacitor 21 and resistance 22. It is apparent that instead of the capacitor 21, an inductive coupling may be used but the capacity coupling is preferred since it is more free from resonance effects, and self-excitation within the cathode-ray tube is thereby avoided. However, if the capacitor 21 is replaced by an inductive coupling, the production of self-sustained oscillations may be substantially reduced by a proper adjustment of the resistances 22, 23 and the proper choice of the voltages employed in the system.

What I claim as new and desire to secure by Letters Patent of the United States, is:

40. 1. In combination, a cathode-ray tube for translating electrical impulses into light rays, said tube including a cathode, an anode, an electrostatic control member and a screen adapted to fluoresce when struck by electrons, energy supply circuits for the electrodes, a source of electrical impulses connected to said control member, and means for transferring electrical energy from the anode of said tube to the control member, said means including an electrical coupling between said anode and control member, whereby control of the electrons through the tube and the variations in intensity of the light spot on the fluorescent screen are enhanced.

55. 2. In combination, a cathode-ray tube for translating electrical impulses into light rays, said tube including a cathode, an anode, an elec-

trostatic control member and a screen adapted to fluoresce when struck by electrons, energy supply circuits for the electrodes, a source of electrical impulses, an amplifier having input and output circuits, said input circuit being connected to said source of impulses, said output circuit being connected to said control member, and an electrical energy feedback connection between said anode and the input circuit of said amplifier for increasing the control exercised on the electron stream in the cathode-ray tube by said control member and for enhancing the variations in the intensity of the luminous spot produced on the screen by electrons.

3. In combination, a cathode-ray tube for translating electrical impulses into light rays, said tube including a cathode, an anode, an electrostatic control member and a screen adapted to fluoresce when struck by electrons, energy supply circuits for the electrodes, a source of electrical impulses, an amplifier having input and output circuits, said input circuit being connected to said source of impulses, said output circuit being connected to said control member, and an electrical energy feedback connection between said anode and the input circuit of said amplifier, said connection including a capacitor.

4. In combination, a cathode-ray tube for translating electrical impulses into light rays, said tube including a cathode, an anode, an electrostatic control member, energy supply circuits for the electrodes, said tube also containing a screen which fluoresces when struck by electrons and an electrode positioned between said control member and the cathode and adapted to be charged positive with respect to the cathode, and an electrical energy feedback connection between said positively charged electrode and said control member whereby the control of the position and the variations in intensity of the luminous spot produced on the screen by electrons are enhanced.

5. In combination, a cathode-ray tube for translating electrical impulses into light rays, said tube including a cathode, an anode, an electrostatic control member, energy supply circuits for the electrodes, said tube also containing a screen which fluoresces when struck by electrons and an electrode positioned between said control member and the cathode and adapted to be charged positive with respect to the cathode, and an electrical energy feedback connection between said positively charged electrode and said control member, said connection including a capacitor.

FRIEDRICH W. HEHLGANS.
